UNITED STATES PATENT OFFICE.

JOHN C. HORNUNG, OF CHICAGO, ILLINOIS.

MOTION-TRANSMITTING APPARATUS.

1,312,692.

Specification of Letters Patent. Patented Aug. 12, 1919.

Application filed October 21, 1918. Serial No. 258,983.

To all whom it may concern:

Be it known that I, JOHN C. HORNUNG, citizen of the United States, residing at Chicago, in the county of Cook and State of Illinois, have invented a certain new and useful Improvement in Motion-Transmitting Apparatus, of which the following is a full, clear, concise, and exact description.

My invention relates to motion transmitting apparatus and has a number of objects and advantages in view. A motion transmitting device made in accordance with my invention enables the positive and quick movement of the load or element to which motion is to be imparted.

My invention has been successfully embodied in an apparatus including two oppositely arranged electro-magnets, an armature between and operable by said magnets alternately, a floating oscillating block pivotally engaged upon one side with a reciprocating portion on said armature, a floating oscillating link having one end pivotally engaged with said block upon a side of the block opposite the place of engagement of the block and said reciprocating portion, a spring pressing upon the other end of said link toward said block and at a place alined with an intermediate position of said armature, and a switching device for alternately energizing said electro-magnets and including current conducting contacting portions on the link upon each side thereof and current conducting contacts between which said link oscillates and complementary to the current conducting contacting portions upon the link. It is to be understood, however, that I do not wish to limit my invention to its preferred embodiment above somewhat specifically described as my invention may be realized in an outfit having fewer elements and characteristics.

When the invention is embodied as specifically described it is of particular use in the quick operation of a load directly actuated by the armature. Such a device has been actually used in controlling the flow of heating fluid for the regulation of temperature to which end the magnets may have their circuits governed by a thermostat in turn regulated by the controlled temperature.

I will explain my invention more fully by reference to the accompanying drawings illustrating the preferred embodiment there-

of and in which Figure 1 is a face view of the apparatus shown in conjunction with valve mechanism and piping, parts being illustrated in section; Fig. 2 is a sectional view on line 2-2 of Fig. 1, a diagram of one circuit arrangement being also included in this figure; Fig. 3 is a sectional view on line 3-3 of Fig. 1; Fig. 4 is a perspective view illustrating a detail construction; and Figs. 5 to 9 inclusive are diagrams illustrative of various stages in the operation of the device.

Like parts are indicated by similar characters of reference throughout the different figures.

The novel portions of the mechanism may be included in a box 1 all parts of which may be made of iron. One electro-magnet includes two spools 2 and 3 having cores 4 and 5 secured to one end wall of the box by means of screws 6. Similarly, the second electro-magnet includes two spools 7 and 8 having cores 9 and 10 secured to the opposite end wall of the box. The cores 4 and 9 are alined as are the cores 5 and 10. The alined cores are spaced apart to accommodate an armature 11 therebetween. This armature is adapted to move back and forth between the magnets and is desirably pivoted at 12 so that the back and forth movements of the armature are swinging movements but I do not wish to be limited to a swinging armature.

If the circuits of the magnets are temperature controlled such a circuit arrangement as that diagrammatically illustrated in Fig. 2 may be employed where I have shown a thermostat 13 adapted to be swung, in response to sufficient temperature changes, into engagement with the contact 14 to include the magnet 7, 8 in circuit with the battery 15 or into engagement with the contact 16 to include the magnet 2, 3 in circuit with said battery. The armature is shown as being in lost motion connection with a valve rod 17 that has adjustable flanged sleeves 18, 19 in threaded engagement therewith and between which the armature is disposed and by the regulation of which sleeves the degree of lost motion between the armature and the valve rod may be regulated or, if desired, eliminated. The valve rod 17 carries a valve 20 having alternate seats 21, 22 for governing flow of fluid through the pipe 23, 24 but as this valve

mechanism forms no novel part of my present invention and as I do not wish my invention to be limited to the character of the load coupled with the armature further description of the valve mechanism need not be given. As illustrated, the seats 21, 22 define the range of armature movement.

Where lost motion intervenes between the armature and the valve rod the armature 10 may have a certain travel from either of its extreme positions toward the other before effecting movement of the valve. At a certain stage in the movement of the armature the device of my invention comes into play 15 to effect quick movement of the armature and thereby of the valve or other load coupled with the armature. An oscillating block 25, which also is desirably a floating block, is pivotally engaged upon one side 20 with a portion 26 that is mounted upon a part of the armature that will impart reciprocating movement to this portion as the armature swings from side to side. This portion 26 may be in the nature of a thin 25 blade of steel whose outer edge that is parallel with the axis of movement of the armature constitutes a knife edge or pivot portion that is received in the notch or pivot seat 27 in the block 25. A floating oscillating link 28 is provided with inturned 30 prongs 29 that are received in an opening 30 that extends through the block 25 parallel to the pivot seat 27. By this arrangement the floating oscillating link 28 has one 35 of its ends pivotally engaged with the block 25 upon a side of the block opposite the place of engagement of the block and armature portion 26. A spring 31 is anchored at one end to a wall of the box 1 and has 40 its other end free to move or flex. The free end of the spring carries a slotted enlargement 32, the slot in which affords a seat for the outer end of the link 28 at which place the spring presses upon said link, this place 45 of pressure being alined with an intermediate position of said armature as indicated in Fig. 6. There is a switching device employed for effecting the alternate energizations of the magnets and this switching device 50 preferably includes current conducting portions on the link 28 upon each side thereof. In the preferred embodiment of the invention the entire link is of metal to be a conductor of current and, as illustrated in 55 Fig. 2, is in permanent connection with one pole of the battery 15. The other pole of the battery is connected by way of the thermostat arm 13, contact button 14, and the electro-magnet 7, 8 with a contact 33 upon 60 one side of the link 28 and by way of the thermostat arm 13, the contact button 16 and the electro-magnet 2, 3 with another contact 34 upon the other side of the link 28, the contacts 33 and 34 being desirably 65 rigid and, of course, complementary to oppos-

ing contracting portions on the metallic link 28, all contacts and the magnets being normally in open circuit.

The diagrams in Figs. 5 to 9 inclusive illustrate various stages through which the device of my invention passes in performing its functions. As I do not desire to limit my invention to a device employing electro-magnets, the element 11 may be termed an arm which may be movable back and forth by means of any suitable agency. In Fig. 5 the arm or armature 11 is shown at one limit of its range of movement, the portion 26 upon this arm being at one side of the median position of the arm or armature 11 and portion 26, which median position is indicated by the dot and dash line 35 in Figs. 5 to 9 inclusive. The floating center or axis of rotation 36 of the floating block 25 is, in Fig. 5, upon the same side of the median line 35 with the element 26. The place of pivotal connection of the link 28 with the block 25 is upon the other side of this line 35, still referring particularly to Fig. 5. When the armature is about brought to its median position as indicated in Fig. 6, the elements 26 and 28 are substantially alined with the floating axis 36 of the floating block 25, this block having now been shifted to bring its axis substantially on the line 35. In moving from the position shown in Fig. 5 to the position shown in Fig. 6, the armature or arm 11 turns in a clockwise direction. As the turning movement of the arm 11 continues in a clockwise direction to the position illustrated in Fig. 7 the shifting axis of the block 25 is moved to the other side of the median line 35 as are also the places of engagement of the part 26 and the link 28 with the floating block. In moving from the position shown in Fig. 5 to the position shown in Fig. 6 the spring 31 was moved outwardly and when the arm 11 is moved to bring the parts to the position shown in Fig. 7 the spring 31 operates to move the link 28 inwardly suddenly. This flexure of the spring is permitted since the place of pressure at 29 of the spring upon the block 25 is movable toward and away from the armature 11. The link 28, in the position shown in Fig. 7, is above the place of engagement of the plate 26 with the block 25 and the link is therefore effective in turning the block about its axis in a counter-clockwise direction to force the rapid turning movement of the block and the rapid movement of the arm 11 to the extreme of its movement from the position shown in Fig. 5 to the alternate position shown in Fig. 9, the energized magnet being then restored to open circuit. The arm 11 may be moved from the position shown in Fig. 9 to that shown in Fig. 5, it being accompanied in this movement by a reversal of the operations just described. In the move- 130

ment of the arm 11 from side to side the link 28 rubs upon the contacts 33 and 34 to maintain them as well as the parts of the link 28 engaging them bright and clean. I prefer to employ the type of spring 31 illustrated and the enlargement 32 which affords a place of engagement of the spring with the link 28 that is alined with the intermediate position of the armature as typified by the dot and dash line 35. I do not wish to be limited however to the type of spring illustrated for exerting pressure upon the link at a place alined with the intermediate position of the armature. The contacts 33 and 34 perform the additional function of defining the range of swinging movement of the floating link 28, these contacts being preferably rigid positively to perform this function.

With reference to the diagrams, Fig. 2 and Figs. 5 to 9 inclusive, it will be understood that the contact 33 is in the circuit of the magnet having the core 9 and that the contact 34 is in the circuit of the magnet having the core 4, the current conducting link 28 being common to these circuits. The circuit of the first magnet includes the contact 14 and the circuit of the second magnet includes the contact 16, the thermostat arm 13 being common to these circuits as it is connected with the floating link 28. The circuit which includes the link 28 and the contact 33 or 34 engaged thereby is the circuit that is closed by the thermostat arm 13 upon its engagement with the contact 14 or 16 that is in the same circuit with the contact 33 or 34 that is in engagement with the link 28. The link maintains engagement with the contact 33 or 34 engaged thereby until the portion 26 is moved by the energized magnet just beyond the median line 35, whereupon spring 31 becomes effective quickly to move the floating link from the contact 33 or 34 engaged thereby to the other one of such contacts. The circuit of the energized magnet is thus maintained until the moment the spring moves toward the floating link and block. The portion 26 having passed the median line, the spring, in its return or inward movement, effects a snapping movement of the link, quickly to open the circuit of the energized magnet and quickly to bring the valve or other load upon the armature to its new position. The inner end of the link which is connected with the floating block 25 moves to the other side of the median line a distance limited by the contact, 33 or 34, newly engaged by the link, thereby introducing an effective component force positively to define the new position of the armature load and positively to partially establish the circuit of the magnet that was not energized, in order that this second magnet may be prepared for energization upon the motion of the thermostat

arm 13 which is to effect this energization of said second magnet. In the circuit arrangement illustrated, the light duty thermostat arm 13 merely establishes one of two gaps in either magnet circuit previous to the establishment of the second gap at 33 or 34, at which latter place the circuit is quickly and positively opened to avoid arcing, the thermostat arm never opening either magnet circuit.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. Motion transmitting apparatus including two oppositely arranged electro-magnets; an armature between and operable by said magnets alternately; a floating oscillating block pivotally engaged upon one side with a reciprocating portion on said armature; a floating oscillating link having one end pivotally engaged with said block upon a side of the block opposite the place of engagement of the block and said reciprocating portion; a spring pressing upon the other end of said link toward said block and at a place alined with an intermediate position of said armature; and a switching device for alternately energizing said electro-magnets and including current conducting contacting portions on the link upon each side thereof and current conducting contacts between which said link oscillates and complementary to the current conducting contacting portions upon the link.

2. Motion transmitting apparatus including two oppositely arranged electro-magnets; an armature between and operable by said magnets alternately; a floating oscillating block pivotally engaged upon one side with a reciprocating portion on said armature; a floating oscillating link having one end pivotally engaged with said block upon a side of the block opposite the place of engagement of the block and said reciprocating portion; and a spring pressing upon the other end of said link toward said block and at a place alined with an intermediate position of said armature.

3. Motion transmitting apparatus including two oppositely arranged electro-magnets; an armature between and operable by said magnets alternately; a floating oscillating block pivotally engaged upon one side with a reciprocating portion on said armature; a floating oscillating link having one end pivotally engaged with said block upon a side of the block opposite the place of engagement of the block and reciprocating portion; a spring pressing upon the other

end of said link toward said block; and a switching device for alternately energizing said electro-magnets and including current conducting contacting portions on the link 5 upon each side thereof and current conducting contacts between which said link oscillates and complementary to the current conducting contact portions upon the link.

4. Motion transmitting apparatus including two oppositely arranged electro-magnets; an armature between and operable by said magnets alternately; a floating oscillating block pivotally engaged upon one side with a reciprocating portion on said armature; a floating oscillating link having one end pivotally engaged with said block upon a side of the block opposite the place of engagement of the block and reciprocating portion; and a spring pressing upon the 20 other end of said link toward said block.

5. A motion transmitting device including a reciprocating portion; a floating oscillating block pivotally engaged upon one side with said reciprocating portion; a floating oscillating link having one end pivotally engaged with said block upon a side of the block opposite the place of engagement of the block and reciprocating portion; and a spring pressing upon the other end of said link toward said block and at a place alined with an intermediate position of said reciprocating portion.

6. A motion transmitting device including a reciprocating portion; a floating oscillating block pivotally engaged upon one side with said reciprocating portion; a

floating oscillating link having one end pivotally engaged with said block upon a side of the block opposite the place of engagement of the block and reciprocating portion; and a spring pressing upon the other end of said link toward said block.

7. Motion transmitting apparatus including electro-magnetic mechanism having an armature movable thereby; a floating oscillating block pivotally engaged upon one side with a reciprocating portion on said armature; a floating oscillating link having one end pivotally engaged with said block upon a side of the block opposite the place of engagement of the block and said reciprocating portion; and a spring pressing upon the other end of said link toward said block and at a place alined with an intermediate position of said armature.

8. Motion transmitting apparatus including electro-magnetic mechanism having an armature movable thereby; a floating oscillating block pivotally engaged upon one side with a reciprocating portion of said armature; a floating oscillating link having one end pivotally engaged with said block upon a side of the block opposite the place of engagement of the block and said reciprocating portion; and a spring pressing upon the other end on said link toward said block.

In witness whereof, I hereunto subscribe my name this fourteenth day of October A. D., 1918.

JOHN C. HORNUNG.
